ECONOMIZER

Filed March 11, 1931

UNITED STATES PATENT OFFICE

HENRY G. GOSSELIN, OF BERLIN, NEW HAMPSHIRE, ASSIGNOR TO BERLIN FOUNDRY AND MACHINE COMPANY, OF BERLIN, NEW HAMPSHIRE, A CORPORATION OF NEW HAMPSHIRE

ECONOMIZER

Application filed March 11, 1931. Serial No. 521,723.

This invention relates to an economizer for utilizing heat from combustion gases which otherwise would be carried out through the chimney and lost. It is an object of the invention to provide an economizer which is economical in construction, efficient in operation, and easy to keep clean. The particular embodiment of the invention hereinafter described in detail is adapted for use with a domestic heating plant.

Various advantageous features of structure will be apparent to one skilled in the art from the disclosure of the invention in the description thereof which follows and on the drawings of which,—

Figure 1 is a perspective view of a typical domestic heater having an embodiment of the invention connected therewith.

Figure 2 is a side elevation of the economizer as shown in Figure 1, a portion of the side wall being broken away to show the interior parts.

Figure 3 is a section on the line 3—3 of Figure 2.

Figure 4 is a section on the line 4—4 of Figure 2.

Referring to the drawings in detail a domestic heater is indicated at 10, this heater being supplied with the usual smoke pipe 11 which leads to a flue in the chimney 12. Between the heater and the chimney the smoke pipe 11 is interrupted by an economizer 13 which may embody the invention. This economizer, as shown, may consist of a back plate 14 which carries a pair of manifolds 15 and 16. These manifolds may, if desired, be cast integrally with the plate 14. The plate 14 is also provided with a pair of connections 17 and 18 which are threaded to receive the ends of an outlet pipe 20 and an inlet pipe 21. Extending from the upper manifold 15 to the lower manifold 16 are a number of pipes 22 which, as shown, may be in zig-zag form, or may be coiled or otherwise disposed in a manner to present a considerable length of piping, and hence considerable surface, to the hot gases within the economizer. As shown, these connecting pipes 22 may each be detachably secured at their respective ends to the manifolds 15

and 16. If desired, each manifold may have an internal partition 23, as shown in Figure 4, dividing the interior manifold into separate chambers. If either manifold is thus provided with a partition, the other is likewise provided with a similar partition. The separate chambers thus formed in the two manifolds are preferably connected respectively with outlet and inlet pipes 24, 25 outside of the economizer, and by one or more connecting pipes 22 inside the economizer.

Projecting forwardly from the back plate 14 are a pair of side plates 30 and 31, a central baffle plate 32, a top plate 33 and a bottom plate 34. Secured to the side, top and bottom plates is a front plate 35. As shown, the baffle plate 32 extends from the back plate to the front plate and from the top plate down to a level somewhat above the bottom plate 34, thus leaving a considerable opening 36 below its lower edge for the passage of combustion gases from one portion of the economizer to the other. The side plates 31 are provided near their upper edges with smoke pipe connections 37 to which the portions of the smoke pipe 11 are attached. The front plate is preferably secured in such a manner as to be readily movable to facilitate cleaning of the exterior surface of the pipes 22 so as to maintain the efficiency of the economizer. A layer of suitable heat insulating material 40 is preferably applied to the entire outer surface of the economizer so as to prevent the excessive escape of heat from the economizer into the surrounding atmosphere. The back plate 14 may be adjustably mounted on a pair of standards each comprising an upright 41 and a foot 42. The two feet 42 preferably extend forwardly as shown to provide a stable support for the economizer. The back plate 14 may be secured to the uprights in any suitable manner as by a pair of collars 43 attached to the plate and fitted on the upright 41, one or both of these collars being supplied with the set screw 44 by which the plate may be firmly secured to the upright. Thus the economizer can be easily installed at any desired height, within limits, suitable for convenient connection with the smoke pipe 11.

In the operation of the economizer, the hot

combustion gases from the heater 10 enter one side of the economizer near the top, pass downwardly and under the baffle plate, then upwardly in the other side of the economizer 5 and out to the chimney 12. The pipes 22 receive considerable heat from the gases to raise the temperature of the water circulating therethrough. The heat thus derived from the combustion gases may be used for any desired purpose. For example the outlet pipe 20 may be connected to the heater 10 so that the economizer serves as a pre-heater for the water entering the heater 10. The separate circulation system through the extra chambers formed by the partitions 23 in the manifolds may be used for any purpose such as 10 heating a radiator in a garage where a temperature of considerably lower degree than that required for a house is sufficient. 15 It is obvious that the heat derived from the economizer can be used in other ways, as desired.

In cases where an oil burner is used in the heater 10, it is usually desirable to have a 20 substantially unobstructed flue from the heater to the chimney when the burner is lighted. For this purpose a damper 50 of suitable size may be provided in the upper portion of the baffle plate 32. This damper 25 may be conveniently controlled by thermo-responsive apparatus indicated at 51. Such apparatus is well known in the art and need not be described in detail. The damper 50 is open when cold so that the open flue is ready 30 for the starting of the heater. When the burner has been lighted the flow of hot combustion gases acts upon the control device 51 and causes the damper 50 to close, thus sending the flow of hot gases down and under the 35 baffle plate 32. When the supply of hot gases ceases and the damper 50 cools off, the control device opens the damper again.

Various modifications and changes may be made in the embodiment of the invention 40 hereinbefore described without departing from the spirit or scope thereof as defined in the following claims.

I claim:

1. A heat-economizer comprising a back 45 plate having an upper and a lower manifold thereon, side plates extending forwardly from said back plate, a smoke pipe connection through the upper portion of each said side plate, removable top, bottom and front 50 plates forming a closed box with said back and side plates a baffle plate within said box having three of its side edges contiguous respectively to said back, front and top plates leaving a clearance between its lower edge 55 and said bottom plate, a plurality of heat-transfer pipe units on either side of said baffle, each said unit being attached at its respective ends to said upper and lower manifolds, and an outside pipe connection on each 60 manifold.

2. A heat economizer comprising a casting 65 consisting of a back plate with an upper and a lower manifold projecting forwardly therefrom, top, bottom and side plates extending forwardly from said back plate, a removable front plate, a smoke pipe connection through the upper portion of each side plate, a baffle plate extending from the back plate to the front plate and from the top plate to a point spaced above the bottom plate, heat-transfer units extending from said upper manifold to 70 said lower manifold, outside pipe connections on said manifolds, and a pair of supporting standards, each said standard comprising an upright shaft adjustably secured to said back 75 plate and a forwardly extending foot at the lower end thereof.

3. A heat economizer comprising a box 80 having top, bottom, front, back and side plates, an upper and a lower manifold projecting forwardly from said back plate, a partition in each said manifold forming two chambers therein, heat-transfer units in said box extending from the chambers of said upper manifold to the chambers of said lower 85 manifold, an outside pipe connection to each of said chambers, smoke-pipe connections through the upper portions of said side plates, and a baffle within said box extending downwardly from the top plate to a point 90 spaced above the bottom plate.

In testimony whereof I have affixed my signature.

HENRY G. GOSSELIN.
